SIGNORS TO HORACE F. GRIFFITH, OF PHILADELPHIA, PENNSYLVANIA.

MACHINE FOR SEALING BOTTLES.

933,549.

Specification of Letters Patent. Patented Sept. 7, 1909.

Application filed October 12, 1908. Serial No. 457,339.

To all whom it may concern:

Be it known that we, EMORY J. GODMAN and WILLIAM H. NIEMEYER, both of the city of Baltimore and State of Maryland, have 5 invented certain Improvements in Machines for Sealing Bottles, of which the following is a specification.

This invention consists principally in the incorporation in a machine for the above 10 described purpose, of appliances whereby after a predetermined and sufficient pressure has been applied to a sealing cap on a bottle to effect a tight closure, the said pressure is maintained substantially without increase or 15 decrease throughout the entire sealing operation, and without respect to any deviation in height (within a reasonable limit) of the bottle from what might be termed the standard size. In other words, by means of the 20 improved mechanism as applied to a machine for sealing bottles, changes in size or shape of the bottle head, or in the height of the bottle within a reasonable limit, has no effect whatever to disturb a predetermined 25 pressure which is applied to the sealing cap at the beginning of the sealing operation, and maintained without change until the sealed bottle is released from the sealing devices.

30 In the further description of the said invention which follows, reference is made to the accompanying drawings forming a part hereof, and in which,—

Figure 1 is a partly sectional side view of 35 the improved machine. Fig. 2 is an enlarged central vertical section of the upper portion of the same. Fig. 3 is a section of Fig. 2 taken on the dotted line $x-x$. Fig. 4 is a section of Fig. 2 taken on the dotted line $y-y$. Fig. 5 is a still further enlarged 40 section of Fig. 2 taken on the dotted line $z-z$. Fig. 6 illustrates a modified construction of a part of the machine, as hereinafter described.

45 Referring now to the drawings 1 is the stand of the machine, and 2 a hollow vertical column secured to the upper portion of the stand.

50 3 is a bar which is placed within the hollow column 2 and adapted to have a vertical reciprocating movement derived from the driving shaft 5 through the medium of the crank 7, and the link 9 which unites the lower end of the bar with the crank pin a .

55 To the upper end of the bar 3 is secured the

sealing head which consists of a cylinder 10 having a bracket b whereby it is connected to the bar 3, and a hollow lug c the sides of which are extended horizontally and engage with a projection d of the column 2 (see Fig. 60 3) and serve to guide the head in its up-and-down motion. The top of the cylinder 10 is closed by a screw plug 12, and its bottom is provided with a mouth-piece 13 which is interiorly flared to facilitate the entrance 65 thereto of the bottle head in the sealing operation hereinafter described. The lower portion of the cylinder 10 for a limited distance beginning at the mouth-piece, is enlarged in internal diameter, and into this 70 enlargement is loosely placed the cylindrical block 15 which rests on an annular shoulder formed on the mouth-piece; and between the block 15 and the underside of the screw plug 12, is confined a stiff coiled spring 16 which 75 is under compression. With this construction, should sufficient upward pressure be applied to the cylindrical block 15 it can be raised until its upper surface comes into contact with the shoulder e formed by enlarging 80 the bore of the cylinder 10 as before described. The cylindrical block 15 for a limited vertical distance beginning at its bottom, is conically bored and fitted with a correspondingly shaped annular capping 85 tool 17 formed preferably of hardened steel; and above this tool, the block is provided with a cylindrical hole f .

19 is a cap-holding spindle whose lower end passes loosely through the hole f in the 90 cylindrical block 15, and extends to near the bottom of the capping tool 17; and the said spindle is supported in this position by a collar g formed thereon, which rests on the top of the cylindrical block. The upper end 95 of the spindle 19 is centralized by the screw plug 12 in which it fits loosely.

20 is a compressed spiral spring, which is confined endwise between the screw plug 12 and the collar g ; and its office is to yieldingly hold the sealing cap on the bottle head, at and prior to the beginning of the sealing 100 operation hereinafter described.

22 is the sealing cap holder consisting of a ring formed in segments which are backed 105 by plate springs h as best shown in Fig. 5. This device is placed between an inwardly projecting lip i in the mouth-piece 13 and the lower surface or edge of the capping tool 17, and is free to expand and contract as re- 110

quired in the bottle sealing operation hereinafter described. The coiled spring 16 offers such resistance to further compression, that in the upward movement of the cylindrical block due to the force necessary to seal a bottle, it will be limited to a distance which is less than that between the said block and the shoulder *e* in the cylinder 10, such distance in view of the angle of the inner conical surface of the capping tool being sufficient to effect the proper closing of the bottle seal around the head of the bottle.

The mechanism which sustains the bottle during the sealing operation, and which yields to admit of the downward movement of the bottle upon the conclusion of the sealing operation, consists of the parts as follows: 24 is a cylinder connected by means of a bracket *j* to the lower end of the column 2, which is in vertical alinement with cylinder 10 of the sealing head. Within the cylinder 24, and adapted to have a vertical movement therein, is another cylinder 25 having a pendent core 27 around which is placed a compressed coiled spring 29 which offers greater resistance to further compression than the spring 16 in the cylinder 10. The upper end of the spring 29 bears against the underside of the head of the inner cylinder 25, and its lower end abuts a plug 30 which is screwed into the outer cylinder 24 and through which the hollow core 27 of the inner cylinder 25 projects. The upward motion of the inner cylinder 25 with its core 27, is limited by a nut *k* which is screwed over the latter device. The core 27 is internally threaded and into it is screwed the stem 32 which passes upward through the core and the head of the inner cylinder 25, and is provided with the bottle seat 33. The bottle seat 33 has a pendent annular flange *m* which fits loosely over the outer cylinder 24. By this construction of the bottle seat, its stem 32 is practically stiffened, and prevented from side deflection, and the interior parts below protected from contact with liquid should a bottle be broken in filling. The stem 32 can be turned by means of a handle 34 at its lower end, to suit bottles differing considerably in height, and when the proper position of the seat is attained, the stem is locked by the nut *n*.

As it is intended that the bottle and its seat shall move downward as soon as sufficient force has been exerted by the capping tool upon the bottle seal to effect a tight closure, and that the pressure upon the cap or seal shall be uniformly maintained until the sealed bottle is released, we employ the appliances which will now be described.

35 is a rack adapted to have an up-and-down movement upon the front face of the column 2. It is guided by the plates *o* as best shown in Fig. 3, and extends when in

its highest position, from near the top of the column 2 to a bracket 36 which projects from the inner cylinder 25 and through a slot in the wall of the outer cylinder 24 of the bottle supporting appliances.

37 is a horizontal shaft journaled in the sides of the hollow lug *e* formed as a part of the cylinder 10 of the sealing head, to which is secured a pinion 39 the teeth of which are in mesh with those of the rack 35, as shown particularly in Fig. 2. The said shaft is also provided with a ratchet wheel 40 which is tight on the shaft, and consequently the pinion 39 and ratchet wheel 40 are susceptible to a common rotary movement.

41 is a shaft similar to the shaft 37, which carries a pawl 42 the point of which is adapted to engage the teeth of the ratchet wheel 40. This pawl has a tail-piece *p* whereby it can be thrown in or out of engagement with the ratchet wheel 40; and it is intended that both of the said actions shall be produced primarily from the capping tool 17 as the same changes its vertical position in and with respect to the cylinder 10.

To effect the operations of the pawl, the cylindrical block 15 is provided with a horizontally extending finger *q* which passes through a slot in the wall of the cylinder 10. This finger is fitted with a vertical spring-supported stem 43 having a head which is slotted for the reception of the end of the tail piece *p* of the pawl 42.

When the parts just described are in the positions shown in Fig. 2, the point of the pawl 42 is out of engagement with the ratchet wheel, and the sealing head can be moved downward without communicating any motion to the rack, the pinion 39 at the time being merely an idler. But should the capping tool with the cylindrical block 15 be pushed upward in the cylinder 10 sufficiently to cause the engagement of the pawl with the ratchet wheel, through the medium of the finger *q*, the slotted head of the stem 43 and the tail piece *p* of the pawl, the rotation of the pinion will be interrupted and that device will in effect become a rigid device. Under these new conditions, the rack is forced downward by the fixed pinion, and by reason of its lower end resting on the bracket 36, the inner cylinder 25 of the bottle supporting devices together with the bottle seat will move in unison with it, and the vertical distance between the bottle seat and the capping tool at the time that the bottle is effectively sealed is maintained until the pawl 42 is again thrown out of gear with the ratchet wheel, which is effected at the termination of the sealing operation now to be described.

Supposing the various parts of the machine to be occupying the relative positions

shown in the drawings, a bottle to be standing on the seat 33, a sealing cap in position within the sealing head, that the strength of the spring 16 in the sealing head be such that 5 the capping tool will perform its sealing function in the downward movement of the sealing head before the cylindrical block 15 has reached the shoulder *e*, that the resistance to further compression of the spring 29 10 which supports the bottle seat, is such as not to be overcome when the cap is properly closed upon the bottle head, and that the sealing head is beginning its downward movement, the machine will operate as follows: Upon the mouth-piece 13 passing over the bottle head, the latter enters the sealing cap which is supported by the ring 22, and in the continued movement of the sealing head, the crown of the sealing cap with its 15 joint-forming gasket is compressed between the bottle head and the lower end of the spring backed spindle 19 sufficiently to produce a tight joint. At this time the bottle is stationary, and in a further downward motion of the sealing head, the capping tool is forced over the sealing cap, and the same brought tightly against the bottle which is sealed, when the capping tool stops. The sealing head continues its downward course 20 independently of the capping tool until the shoulder *e* approaches the cylindrical block 15 which carries the capping tool. When the bottom of the slot in the head of the stem 43 reaches the tail-piece *p*, and through it 25 throws the point of the pawl into engagement with the teeth of the ratchet wheel 40 which together with the pinion 39 have been rotating, due to the latter being in mesh with the rack 35. In the locking of the pinion 39 through the agency of the ratchet wheel and pawl as described, the pinion becomes a 30 fixed device which causes the rack to descend with the sealing head, and as its lower end bears on the bracket 36 of the bottle supporting devices, the spring 29 is overcome and the seat 33 is forced down together with the bottle which remains under a uniform strain until in the rise of the sealing head it is released when the rack, pinion and 35 ratchet mechanism assume their original positions and the machine is in condition for another sealing operation similar to the one described.

It will be understood that in sealing bottles with our improved machine, a predetermined maximum sealing pressure upon the bottles effected by the strength of the spring 16, is in all cases applied, notwithstanding that the bottles may differ within a reasonable limit in length, and that the predetermined pressure cannot be increased, for the reason that upon the same being attained, the bottle descends in unison with the sealing devices.

In the construction of the sealing head as

above described, the mouth-piece 13 is subjected to the combined downward force of the coiled springs 16 and 20, and should a bottle be crushed in the sealing operation when the cylindrical block 15 is in its highest position with respect to the cylinder 10 of the sealing head, the sudden extension of the springs would cause the cylindrical block to strike the mouth-piece after the manner of a hammer, which might produce the dislocation of or injury to that device. This danger is entirely obviated in the construction shown in Fig. 6 in which an offset vertically moving ring 45 supported by a projection *r* in the cylinder 10, receives the pressure of the two spiral springs, the cylindrical block bearing on the mouth-piece with a force due to its weight only. This alternate construction does not in any manner affect the sealing operation performed as described. 85

We claim as our invention,—

1. In a machine for sealing bottles, a yielding bottle support, a sealing head comprising a spring-backed capping tool susceptible of an up-and-down movement therein, and means whereby the head including the capping tool, is brought down toward and independently of the bottle support, combined with mechanism whereby in the arrest of the downward motion of the capping tool independently of the sealing head, movement is communicated to the bottle support, and all the said elements are depressed in unison, substantially as specified. 90

2. In a machine for sealing bottles, a yielding bottle support, a sealing head comprising a spring-backed tool susceptible of an up-and-down movement therein, and means whereby the sealing head including the capping tool, is brought down toward, 105 and independently of the bottle support, combined with locking devices which become operative in and by the arrest of the downward motion of the capping tool independently of the sealing head, and communicate the motion of the sealing head including the capping tool to the bottle support, whereby all the said elements of the apparatus are depressed in unison, substantially as specified. 110

3. In a machine for sealing bottles, a yielding bottle support, a sealing head comprising a spring-backed capping tool, and means to move the head including the capping tool toward the bottle support, combined with appliances actuated by the arrest of the downward motion of the spring-backed capping tool independently of the sealing head, which effect a common downward motion of the sealing head and the yielding bottle support, and thereby maintain a uniform distance between them during their depression, substantially as specified. 120

4. In a machine for sealing bottles, a 130

yielding bottle support, a sealing head having therein a spring-backed capping tool, and means to move the head toward and from the bottle support, combined with appliances actuated by the arrest of the downward motion of the spring-backed capping tool independently of the sealing head, which serve to lower the bottle support in common with the sealing head and the capping tool, during the period that the said tool is occupying its changed position with respect to the sealing head, thus preserving a uniform distance between the capping tool and the bottle support during the entire sealing operation, substantially as specified.

5. In a machine for sealing bottles, a stationary columnar stand, a yielding bottle support on the stand, a rack having a vertical sliding movement on the columnar stand adapted in its downward motion to

depress the bottle support, combined with a sealing head embodying a spring-backed capping tool, means to vertically reciprocate the sealing head with its capping tool, an idle pinion carried by the sealing head, which pinion is in mesh with the rack, a ratchet wheel arranged to rotate in common with the pinion, and pawl mechanism actuated primarily from the capping tool which in the arrest of the movement of the capping tool serves to suspend the rotation of the ratchet wheel and pinion, whereupon the latter effects a downward motion of the rack and through it depresses the bottle support, substantially as specified.

EMORY J. GODMAN.
